ELECTRICAL TRANSMITTING MEANS FOR
SPEAKING ANNOUNCEMENTS

Albert Findlay, Montreal, Quebec, Canada, assignor to John B. Frosst, Westmount, Quebec, Canada

Application August 9, 1938, Serial No. 223,931

5 Claims. (Cl. 179—6)

The invention relates to an electrical transmitting means for speaking announcements, as described in the present specification and illustrated in the accompanying drawings that form part of the same.

5 The invention consists essentially in establishing an operating connection from an electric transmission line to a talking machine, voicing record messages denoting the time of day or night and sundry other matters, as pointed out in the claims for novelty following a description in detail of the parts and the operation throughout.

The objects of the invention are to furnish to the public an automatic inquiry bureau in which the answers are prepared previous to the interpellation of the person requiring the information and delivered in the way of an automaton such as answering the oft repeated question, "what is the time of day" whereby the trials of the telephone operator in answering calls are very much relieved by having the uninterrupted announcements made repeatedly from minute to minute or from second to second as desired, and always subject to tapping by any person desiring to know the time during the day or night while the telephone service is operating; and to make, if required, inserts in the information that will announce other good news to the public in the way of advertising or various pieces of information usually often in the form of stock phrases, and otherwise, and generally to add to the conveniences of the telephone services at large.

In the drawings,

Figure 1 is a front elevational view showing the lamp signals arranged in numerical order round the circle and the electric eye on the revolving arm passing over the circle.

Figure 2 is a side elevational view of the telephones and the lifting mechanism for the receivers.

Figure 3 is a diagrammatical view showing the hollow shaft with the rod carrying the electric eye and the commutator.

Figure 3a is a front elevational view showing of signal lamps with connection to amplifier.

Figure 4 shows a diagrammatical view of the wiring of the manual monitor switchboard for the operation of the key circuit with emergency key.

50 Figure 5 shows the speaking clock amplifier circuit for the electric eye.

Figure 6 shows a diagrammatical view of the batteries for power supply.

Figure 7 shows a filament circuit.

Figure 8 is a front elevational view showing the terminals of the amplifier.

Figure 9 shows a plan view of the clutch mechanism connected to the fibre plate elevating rod.

Figure 10 is a front elevational view of the announcing table.

Figure 11 is a plan view of the announcing table with the cover removed.

Figure 12 is a diagrammatical view of the wiring of the announcing table.

Figure 13 shows a commutator circuit for the peg counter.

Figure 14 is a front elevational view of the commutator.

Like numerals of reference indicate corresponding parts in the various figures.

Referring to the drawings, the illustrations include a telephone system which is of the standard type. For this invention, no additions are made to the telephone apparatus and this is particularly emphasized in Figures 1 to 4, and Figures 10 and 11. Figure 1 shows the continuously rotating electric eye cooperating with a plurality of lamps arranged in a circle in two groups for completing the call system independently of the regular service, and this cooperation is made through a relay system more particularly described hereinafter through the connection made in each instance and this connection serves to lift the telephone receiver concerned, thus establishing a connection for the caller, and the announcement of the time is now over a loud speaker from an announcing table by gramophone records specially recorded to encompass every twenty-four hours per day. The manual system described hereinafter is only used when adjustments are required to the automatic announcer.

In the manual system, standard types of ringing box and lamp signals 16 may be used in conjunction with this invention or a switch button or lever, for it is the purpose of this invention to make use of the light rays given out by the said lamp signals 16, thereby identifying the calling light. In the lamp signals each group is in numerical order around the circle 17 and an electric eye 18 revolves on a hollow arm 19 passing over the circle, thereby creating impulses in harmony with the lamps that might be lit during the revolution of the arm.

A sensitive relay 20 is incorporated in the electric eye circuit which is associated with the commutator 21 above the revolving arm, causing the relay to pulse whenever affected by the light rays and commutating a group of individual relays 22. The telephone receivers 23 are raised from the

switch hooks 24 by means of a small fibre plate 25 fastened to a rod which is in turn associated with a clutch mechanism 26. When the receiver is in the lifted position, the time announcement 5 is given and swelled over a loud speaker and the receiver is replaced by the restoring of the relay, the fibre plate 25 being one half inch away from the telephone receiver 23 when in normal position, thereby isolating the public telephone 10 equipment from the mechanism of this invention.

In any city there are certain demands for a service that will provide for the giving of actual 15 clock time upon demand usually by telephone and, as the total of these demands is directly proportional to the number of connected public 20 telephones in any particular area and the fact remains the time announcement number is always available, the same time announcement can be given to all the connected calling parties that 25 happen to call simultaneously.

In Figure 4, the operating key 27 is shown in its neutral position, and this key has three positions, the calling position, the neutral position and the announcing position, when the arm for 25 the electric eye is passing over the circle it creates impulses in harmony with the lamps that might be lit during the revolution of the arm.

It will be seen that this invention provides a time service upon demand by telephone without 30 connecting any wires or mechanical attachments to the telephone companies equipment.

The above description refers to a manual system whereby telephone operators move the control key on the monitor switchboard to the three 35 operating positions; first, collecting all incoming calls; second, announcing position; third, cancelling position after calls have been responded to. Figure 4 shows a diagram of the circuits employed.

40 Figure 2 shows a mechanical method of automatically controlling the system without the aid of the monitor switchboard or telephone operators. Time announcements are made by means of gramophone records 28 and 29 specially recorded to encompass every minute of the twenty-four hours per day. The manual system is only used when adjustments are required to the automatic announcer.

45 It will be seen from the drawings that two turntables 30 and 31 are employed and are directly connected to a drive shaft 32 so that they are synchronous with each other. Placed upon each turn table is a gramophone record. One of these records 28 is termed as a pre-announcement that is always engaged before the second record 29, the purpose being to supplement the time announcement with an interchangeable advertising slogan or any other desired message that can be changed at will.

50 The record 29 is the time announcement record and is engaged only after the conclusion of the pre-announcement; for example:—As an advertising announcement, the cycle would be the record 28 announcing "John Doe's Cigarette Time". The electric "pick up" is automatically lifted from the record and held clear of the record preventing a repetition during a cycle.

55 The second "pick up" now drops on the record 29, announcing the correct time at that particular moment, the complete announcement would then be as follows:—(of responding to a telephone call at 10.25).

"John Doe's Cigarette Time—Ten Twenty-Five—Dix Heure et Vinte Cinq."

75 Following the complete announcement, the au-

tomatic machine cancels all the engaged telephones that were being responded to and then automatically changes to the collecting position to accept new telephone demands that accumulated during the announcing cycle. As soon as 5 the electric eye 18 completes a revolution in front of the telephone lamp signals, the associated relays are operated and locked in the circuit controlling the telephone receivers. At the completion of the revolution of the electric eye 18, the 10 automatic announcing machine changes the circuits to the announcing condition and holds the said circuits until the time announcement is completed and then completes the cycle by canceling the holding circuit releasing all relays to 15 normal.

In the event of an amplifier tube becoming defective, the electric eye circuit will not function; therefore, an auxiliary circuit is provided that causes half the connected telephones to lift the 20 receivers irrespective of whether the lamps are lit or not, the other half are left free for incoming calls while the time announcing is being made, and as soon as the announcement is completed, the circuit holding the first group 25 of telephones is released and the second group is then connected and the continuous alternating of the two circuits causes one group to be free while the other is in operation. This feature is only used as an emergency and is also duplicated 30 on the manual switchboard.

The above circuits are controlled by a series of cams 32a and contacts, as shown on the drawings; the said cams being attached to the common drive shaft 33 and a two to one ratio auxiliary shaft 34. The said shafts are directly connected to the gramophone turn-tables 35 and 36 and driven by a synchronous type of motor 37 to assure uniformity of speed of the turn-tables.

Two special "pick ups" 38 and 39 are incorporated in the device and are joined together with an equalizing arm 40 to assure accuracy of position relative to the records and the correct time, and each "pick up" drops on the record by means of a cam control 41 causing an announcement to 45 be made. The cams are designed to permit the "pick up" 38 to drop and raise before the "pick up" 39 drops to make the time announcement, when the announcement is completed both "pick ups" are clear and above the records. This operation is repeated a number of times between 50 each successive minute thereby announcing the same time for a period of sixty seconds.

Incorporated in the announcing machine is a graduated cam 42 with sixty different positions 55 termed a sixty point snail which controls both "pick ups"; this snail is driven every minute from one point to the next thereby advancing the "pick ups" one space which corresponds to the next minute space recorded on the gramophone records. When the "pick ups" drop a new minute 60 will be announced. Each gramophone record has sixty different announcement grooves and are automatically changed after the fifty-ninth announcement by the usual type of record changer 65 with modifications to synchronize the changes between announcing periods.

A master clock 43 and a group of telephone relays transmit the one minute impulses to the driving mechanisms, Figure 12 shows the circuits 70 employed which holds the graduated snail from advancing before the completion of an announcement should a clock impulse be sent out during the cycle of announcement. The circuit operating relay DR prevents the electric eye from col- 75

lecting calls during the change of records. When a new record is automatically placed on the turn-table, DR relays are released and the electric eye 18 again functions causing the telephone receivers to raise and receive an announcement of the even hour.

Figure 13 shows a commutator circuit that causes a peg counter 44 to indicate and accumulate the number of calls responded to. It will be seen by Figure 3 that each relay is wired to a contact point on the commutator 21, the commutator wiping brush passes over the said contacts and should battery current be on any particular contact associated with one of the operated 15 relays, it will cause the peg counter 44 to register, there are as many points as there are connected telephones provided for on the commutator.

Associated with the time announcement machine is an additional service whereby time announcements and advertising media is transmitted over a metallic circuit to any desired 20 location remote from the announcing machine.

The purpose of this is to permit the use of a speaking clock in public places or residences 25 whereby time announcements may be obtained by a push button or other means on the speaking clock that provides a direct connection to the announcement machine and functions as described for the same system of demands by telephone.

What I claim is:

1. In an electrical transmitted speaking device, a sensitive relay incorporated in an electric eye circuit, a commutator associated with said circuit, a revolving arm carrying said electric eye circuit causing said relay to pulse whenever effected by the light rays from a group of lamp signals and commutating another group of individual relays, a plurality of telephones asso-

ciated individually with a particular relay and lamp signal.

2. In an electrical transmitted speaking device, a sensitive relay incorporated in an electric eye circuit, a plurality of telephones, a rod 5 having a fibre plate attached thereto adapted to raise the receiver of said telephones, and a clutch mechanism associated with said shaft, a loud-speaker announcing the time when the receiver is in its raised position and means for replacing 10 said receiver after the announcement has been made.

3. In an electrical transmitted speaking device, a sensitive relay incorporated in an electric eye circuit, a commutator associated with said circuit, lamp signals in two groups placed in a circle 15 in numerical order, a revolving arm carrying said electric eye circuit and passing over the circle, thereby creating impulses in harmony with the lamps that might be lit during the revolution of 20 the arm.

4. In an electrical transmitting speaking device, a sensitive relay incorporated in an electric eye circuit, a plurality of telephones, electrical and mechanical means for raising and replacing 25 the receivers of said telephones, an auxiliary circuit adapted to take the place of said electric eye circuit, as in emergency.

5. In an electrical transmitting speaking device, a sensitive relay incorporated in an electric 30 eye circuit, a commutator associated with said circuit, acoustical means for transmitting time announcements, an announcing table comprising two turn tables, a drive shaft directly connected to said turn tables and means for transmitting the impulses from a master clock to a 35 driving mechanism for the correct time announcement.

ALBERT FINDLAY.
